UNITED STATES PATENT OFFICE.

GEORGE J. RICHARDSON, OF PETERSBURG, VIRGINIA, ASSIGNOR TO AMERICAN SPOT-LESS STREET SYSTEM, INC., OF PETERSBURG, VIRGINIA, A CORPORATION OF VIRGINIA.

DESIGN FOR A COMBINED TRASH-RECEPTACLE AND ADVERTISING-CARRIER.

57,379.

Specification for Design.

Patented Mar. 15, 1921.

Application filed June 30, 1920. Serial No. 393,191. Term of patent 14 years.

To all whom it may concern:

Be it known that I, GEORGE J. RICHARDSON, a citizen of the United States, residing at Petersburg, in the county of Dinwiddie and State of Virginia, have invented a new, original, and ornamental Design for a Combined Trash-Receiptacle and Advertising-Carrier, of which the following is a specification, reference being had to the accompanying drawing, forming part thereof, and in which—

Figure 1 is a perspective view of the com-

bined trash receptacle and advertising carrier showing my new design.

Fig. 2 is a plan of the same.

I claim:—

The ornamental design for a combined trash receptacle and advertising carrier, as shown.

GEORGE J. RICHARDSON.
